UNITED STATES PATENT OFFICE.

JOHN F. GODFREY, OF ELKHART, INDIANA, ASSIGNOR TO THE GODFREY CONVEYOR CO., OF ELKHART, INDIANA, A CORPORATION OF INDIANA.

MAST SADDLE.

Application filed September 9, 1921. Serial No. 499,505.

To all whom it may concern:

Be it known that I, JOHN F. GODFREY, a citizen of the United States, residing at Elkhart, in the county of Elkhart and State of Indiana, have invented certain new and useful Improvements in Mast Saddles, of which the following is a specification.

This invention relates to a new and improved mast saddle and more particularly to a device of this character adapted for use in securing cables to tops of masts in connection with cableway conveyors.

In the construction of cableway conveyors, it is common practice to secure the main track cable to the mast head and then to guy the mast independently to dead men. This makes a rather awkward construction, in that it makes it difficult to take up slack in the track cable and requires the introduction of turn buckles or the equivalent at the junction of the cable and mast head. The track cable in such conveyors becomes slack during use and must be tightened by the turn buckles at the mast head. This tightening must be done upon the top of the mast.

A further difficulty with such construction lies in the fact that the turn buckle prevents the conveyor trolley from closely approaching the mast head.

It is an object of the present invention to provide a mast saddle adapted to receive the track cable of a cableway conveyor and to permit the end of this cable to extend downwardly to the ground.

It is an additional object to provide a saddle wherein lateral guy cables are secured in place and where such guys may consist of a single cable extending over the mast cap and clamped thereon.

It is a further object to provide a device which is simple in design and construction and which may be readily and easily applied and adjusted. Other and further objects appear as the description proceeds.

In the form of my device which I have selected for purposes of illustration, the mast saddle comprises a body member adapted to be secured to the top of a mast, this member having a longitudinally extending seat formed therein for the reception of the track cable. The seat has its rear portion inclined downwardly so that the cable may be extended to the ground without a sharp bend.

Clamps are provided for securing the cable

in place relative to the saddle. A laterally extending groove is provided for the reception of transversely extending guy cable. This groove is upon a different level so that the guy cable clears the track cable. Means are provided for clamping the guy cable independently of the track cable.

I have illustrated a preferred embodiment of my invention in the accompanying drawings, in which,

Figure 1 is a side elevation of the device;

Figure 2 is a plan view of the body member;

Figure 3 is a view of Figure 1 as seen from the right;

Figure 4 is a section taken on line 4—4 of Figure 2, and

Figure 5 is a section taken on line 5—5 of Figure 2.

Referring now to the drawings; the body member 6 is provided with the downwardly extending shoulders 7 adapted to engage the mast head and with the bolt holes 8 by means of which the member is secured in place upon the mast head. The longitudinally extending groove 9 is provided, the rear portion of this groove inclining downwardly as best shown in Figure 1.

A pair of clamping members 11 are secured in place upon seats 12 formed on the body member, by means of bolts 13. As shown in Figures 3 and 4, these clamping members 11 are provided with grooves 14 to firmly engage the cable. A transverse groove 15 extends on a lower level than the groove 9 and its lateral portions 16 are inclined rearwardly and downwardly and pass between seats 17 upon which are secured clamping members 18, by means of bolts 19.

In the use of the device, the body member or saddle is secured firmly in place upon the mast head. The track cable is passed over the saddle, fitting in the groove 9 and extending downwardly from the rear portion 10 to the ground where its end is secured to a dead man or an equivalent device.

A turnbuckle or similar member may be placed in the cable adjacent the ground without in any way shortening the effective length of the track. When the track cable is properly tightened the clamps 11 are brought to bear to hold it firmly clamped to the saddle. In this way the track cable serves as a backstay.

Lateral stays or guys may comprise a single

cable extending across the cap track grooves 15 and 16 with its opposite ends secured to the ground. When proper adjustment is secured the clamps 18 are brought to bear 5 upon the cross cable.

If an independent back stay is used, the main track cable need not be clamped upon the saddle, and it can then be adjusted from the ground without sending a man to the 10 mast top. If the track cable is used as a backstay, the clamps 11 must be loosened before tightening the cable. The tightening, however, may be done from the ground. This is a much simpler proposition than 15 sending a man to the mast top to do the tightening at that point.

The play over the top of the saddle assures equal pull upon the side guys which are adjusted before they are clamped. Additional 20 backstays may be readily used by simply looping them around the front of the mast either above or below the main track cable.

The device is simple in design and may be 25 readily installed and adjusted. It is composed of but few parts and is adapted for commercial use and production.

It is my intention to cover all modifications of my device coming within the spirit 30 and scope of the following claims.

I claim:

1. A mast saddle comprising a body member adapted to be secured to a mast top, said body having grooves for the reception of 35 cables, and clamping members associated with the body member and adapted to secure the cables in place.

2. A mast saddle comprising a body member adapted to be secured to a mast top, 40 said body having grooves for the reception

of cables, said grooves crossing each other and being upon different levels whereby cables therein clear each other, and clamping members associated with the body member and adapted to secure the cables in place. 45

3. A mast saddle comprising a body member adapted to be secured to a mast top, said body having grooves for the reception of cables, said grooves crossing each other and being upon different levels whereby cables 50 therein clear each other, and a pair of clamping members associated with each groove, the clamping members of each pair being located upon opposite sides of the intersection of the grooves. 55

4. A mast saddle comprising a body member adapted to be secured to a mast top, a longitudinal groove in said body member adapted to receive a track cable, a transversely extending groove adapted to receive 60 a guy cable, the grooves being upon different levels whereby cables therein clear each other, and means for clamping the guy cable upon either side of the track cable.

5. A mast saddle comprising a body member adapted to be secured to a mast top, a longitudinal groove in said body member adapted to receive a track cable, the rear portion of the groove being inclined downwardly, a transversely extending groove 70 adapted to receive a guy cable, the lateral portions of the groove inclining downwardly and to the rear, the grooves being upon different levels whereby cables therein clear each other, and means for clamping the guy 75 cable upon either side of the track cable.

Signed at Elkhart, Indiana, this 6th day of Sept., 1921.

JOHN F. GODFREY.
